CONVERTIBLE SEAT BED

Joseph R. Thomas, Chicago, Ill.

Application December 17, 1951, Serial No. 261,953

18 Claims. (Cl. 5—13)

This invention relates in general to a convertible seat of the folding chair or davenport type and is more particularly described as an improved folding seat mechanism in which the seat section is inverted rearwardly in changing it from a seat to a bed form.

An important object of the invention is to provide a convertible seat bed having an improved seat folding mechanism by which the seat section is inverted rearwardly and the other bed sections are moved upwardly and outwardly over a fixed front rail with the movements of all of the seat sections coordinated by the folding mechanism as the construction is changed from a seat to a bed and is returned from extended bed position to form a seat.

Other objects of the invention are to provide a convertible seat structure which provides for a fixed front rail connecting the ends of the seat frame within and over which some of the folding sections are movable in order to change it from one limiting position to the other; to provide positive coordination of the overturning of the seat with the controlled unfolding of the other bed sections; to provide for easier operation of the folding structure at the start of the closing operations; to provide a unitary folding construction which is adapted to be applied to and removed from a chair or davenport frame for easily setting up a complete article of furniture and for partially dismembering it for shipment and storage; to provide improved counterbalancing and unfolding movements of the sections which are supported in an intermediate position by one of the legs in the folding and unfolding movement; to provide a convertible seat structure with a fixed front rail, of full height and coordinated folding sections to move automatically over the rail, which contribute to the practice of good and improved design and freedom in styling of furniture of this type; and in general, to produce the structure herein shown and described.

Other objects will appear hereinafter, the preferred embodiment of the invention being illustrated in the accompanying drawings in which,

Fig. 1 is a side elevation of the convertible seat structure in accordance with this invention, the seat frame being in section to show the folded structure more clearly.

Fig. 2 is a side view of the folding structure of Fig. 1 in a raised intermediate position.

Fig. 3 is a side view of the folding structure in a partially lowered intermediate position.

Fig. 4 is a side elevation of the structure in inverted or bed position.

Fig. 5 is a plan view of a portion of the inverted structure as shown in Fig. 4.

Fig. 6 is a perspective view of the connecting and coordinating linkage as shown approximately on the line 6—6 of Fig. 5.

Fig. 7 is an enlarged detail plan view as taken approximately on the plane 7—7 of Fig. 4; and

Fig. 8 is a detail sectional view as taken on the line 8—8 of Fig. 6.

2

In convertible furniture of the overturning seat type, it has heretofore been difficult to provide a sufficiently rigid connection for the frame ends of the supporting arms and at the same time to provide a fixed front board 5 of sufficient height at the front of the frame so that a pleasingly upholstered article of furniture may be produced.

In the present invention, a relatively high front board is fixed in position and the folding structure is first raised 10 from below the seat to clear the top of the front board and to unfold outwardly and downwardly in a controlled movement without requiring a heavy lifting operation at any stage of the folding or unfolding movement.

Referring now more particularly to the drawings, this invention comprises a mounting frame which may be in the form of a chair or a davenport having side frames or ends 10 connected by a back 11 and the fronts of the ends connected by a front board 12. No special provision is made for covering or upholstering this frame but it is usual to provide a back cushion 13 which has a lower fixed rail 14 below and partially behind which some of the mechanism swings in changing the construction from a seat to a bed. The invention comprises particularly the metal folding sections which are mounted 20 at the inside of the frame ends 10 and are adapted to swing from a seat position within, below and partially behind the lower end of the back cushion 13 outwardly over the fixed front board 12 into an extended position partially within the frame and in front thereof. The fixed front board is an advantage in holding the frame parts firmly in position.

The metal folding construction comprises a seat section 15, an intermediate section 16 and an outer section 17. These sections are usually composed of metal angle bars 35 within which are connected wire fabric constructions 18 in the front and intermediate sections and flat metal strips 19 in the seat section. These fabrics are drawn tightly in each section by helical springs 20 and extend throughout each section, together forming a bed bottom 40 when the sections are extended for supporting a mattress and bed clothes. The seat section in particular provides a surface upon which a seat cushion may be secured or loose cushions may be freely deposited in a well known manner.

In changing the folding construction from a seat to a bed, the seat section which is uppermost, as shown in Fig. 1, is overturned rearwardly within the frame and the intermediate and outer folding sections are swung upwardly over the fixed front rail while the seat section is being overturned within the frame and then the intermediate and outer sections are moved outwardly and downwardly into alignment with each other and with the seat section overturned within the frame as shown in Figs. 4 and 5.

The seat section comprises angle bars 21 at each end 55 connected by a cross bar 22 which is at the front of the frame in uppermost position as shown in Fig. 1, and near each end or at the middle of the cross bar is a pivoted latch 23 adapted to engage in a notch 24 near the upper edge of the inside of the front board 12.

At each end of the seat section is a spacing plate 25, preferably a short piece of angle bar which has one web attached by rivets or fastening bolts 26 to one web of the angle bar 21 and another web parallel to the other web of the angle bar but spaced therefrom as 65 clearly shown in Figs. 5 and 6 which provides a support for an irregular fixed mounting bar 27 secured to the other web of the spacing plate by rivets 28. One extremity 29 of this mounting bar extends a short distance from the end bar 21 and the other extremity 30 extends further away from the bar 21. To the extremity 29 is pivoted one end of a link 31 which is in the shape of a

bell crank, and the other end of the link is connected by a pivot 32 with a mounting strap 33 which is adapted to be secured to the inside of the adjacent frame end 10 by fastening screws 34. To the other end of the mounting strap, one end of a lever comprising an arm 35 is connected by a pivot 36 and the other end of this arm has a plate 37 rigidly attached thereto with an offset 38 adjacent its connection with the arm. The other end of this plate 37 is connected by a pivot 39 with the extending end 30 of the irregular mounting bar 27. Thus the seat section is pivotally mounted for overturning movement within the seat frame by these two members, the link 31 and the lever 35, 37 which are connected to opposite ends of the irregular mounting bar 27. The ends of the mounting strap 33 are preferably offset outwardly as shown more clearly in Fig. 5 so that the pivots 32 and 36 of the mounting links will not engage the ends and the members 31 and 35 will be spaced inwardly and from each other and so that the bell crank link 31 will be seated in the space provided by the spacing plate 25 when the seat section is at rest in the seat position as shown in Fig. 1.

At this time, the seat section is supported by an angle bracket 40 (at each end) secured to the end frame 10 by fastening screws 41 and projecting inwardly therefrom below the mounting strap 33. It is in this position that the pivoted latch 23 (or latches) at the adjacent side of the seat section is turned into engagement with the notch 24 at the upper edge of the front board.

In order to cushion and assist the overturning movements of the seat section, a coil spring 42 is connected at one end to a point 43 substantially in the angle of the bell crank link 31 and it is connected at its other end to a projection 44 from the end of the arm 35 adjacent but at one side of its pivot 36 by which it is connected to the strap 33. The pull of this spring tends to raise the seat section in the frame.

Extending upwardly from the seat section in its seat position is a strengthening yoke 45 which has a fastening 46 at each end connected with one of the side rails 21 and joining and strengthening it at this side which is opposite the fixed rail 22 at the other side of the section. This yoke is strengthened and positioned at each end by a link 47 connected at one end to the inside of the adjacent angle bar 21 and connected by a fastening 48 at the other end with the adjacent side of the yoke 45 intermediate the upper and lower portions of this side so that the yoke is held firmly in its extended position. The cross piece of the yoke 45 is thus spaced materially below the mattress supporting fabric (18, 19) of the bed so that it will not be engaged even though the weight of a person upon the bed is sufficient to depress the mattress and the wire fabric to a considerable extent. Likewise when the seat is in a folded condition, this yoke is disposed at the rear of the frame and substantially below and behind the fixed rail 14.

Extending laterally from the plate 37 is an abutment 49 preferably formed integrally by bending it therefrom, and this abutment engages the bent extremity 30 of the irregular mounting bar 27 in one direction of movement to limit the movement of the seat section in the bed forming position as shown in Fig. 4.

Between the intermediate section 16 and the seat section 15, there is a double connection at both ends of the sections. One connection consists of a link 50 connected at one end by a pivot 51 to the adjacent side of the yoke 45 near the outermost portion thereof, and the other end is connected by a pivot 52 with a side bar 53 of the intermediate section 16. The other connection includes a coordinating lever 54 having a bent extremity 55 and connected by a pivot 56 adjacent the angle of the bent extremity 55 to the end of the adjacent angle bar 21. The end of this bent extremity 55 is connected by a pivot 57 with one end of a short link 58,

the other end of which is connected by a pivot 59 with the free end of the plate 37 which is attached to the link 35. This link 58 has a limited movement on the plate in one direction and a stop 60 is positioned thereon to engage the link when it is moved in that direction. This likewise limits the movement of the lever 54 when it is swung about its pivot 56.

The connection of the seat mounting parts with the link 50 and the coordinating lever 54 by means of the short link 58 automatically controls the overturning movement of the seat in changing it from a seat to a bed construction (and from a bed to a seat) and also coordinates the action of the seat with the folding movement of the other sections.

The other end of each coordinating lever 54 has a bent extremity 61 connected by a pivot 62 near one end thereof at one side of a plate 63 secured to one end of the angle bar 53 at each end of the section 16. The end of the extremity 61 is connected by a pivot 64 with a leg folding lever 65. The other end of this lever 65 is connected by a pivot 66 with a hinge plate 67 secured to a side angle bar 68 of the outer bed section 17. The side bar 53 of the intermediate section is connected to this same plate 67 by a pivot 69 so that these two side bars 53 and 68 will rotate about each other from a right angle position as shown in Fig. 1 to a position in alignment with each other as shown in Figs. 4 and 5. The lever 65 also coordinates the folding of sections 16 and 17.

A leg 70 is pivoted to each plate 63 at the side opposite the connection of the lever 54 by a pivot 71 and the two legs at opposite sides of the sections are joined by an angle bar cross base 72. Near its pivotal mounting, a plate 73 is secured to each leg which has a pivot 74 engaging one end of a link 75, the other end of the link being connected by a pivot 76 with the coordinating lever 65 adjacent its pivotal connection with the coordinating lever 54. The unfolding movement of the sections 16 and 17 from a position as shown approximately in Fig. 2 to that shown in Fig. 3, causes a quick unfolding movement of the intermediate supporting legs 70 before the bed sections reach their position of alignment which helps to support them for their final or aligning movement.

To assist the folding movement of these legs 70, a coil spring 77 is connected at one end to the cross bar 72 adjacent each leg and the other end of each spring is connected to the bar 53 slightly inwardly from the pivot 71 of the leg itself so that in the folding movement of the construction when the outer end is raised, the springs 77 will assist the inward folding movement of the legs 50 when the outermost section 17 is raised.

A pair of legs 78 are pivoted to the opposite side bars 68 of the outer section 17, one at each side thereof, by means of a pivot 79 intermediate the ends of the side bar 68, the legs being joined by a cross bar 80 intermediate the top and bottom thereof. To automatically fold these legs 78, a link 81 has a pivot 82 at one end connected near the upper end of one of the legs 78 and the other end of the link has a pivot 83 connecting it to the leg folding lever 65 adjacent to its pivot 66. The outer ends of the side bars 68 are connected by a cross bar 84 which is continuous therewith or firmly secured thereto to provide with the cross bar 80 sufficient strength and resistance to a collapsing movement of the bed sections due to a weight or load thereon.

When the mechanism is folded within the seat frame, the sections 16 and 17 with their connections are swung below the seat section and at the rear of the frame partially behind the seat section and below the back cushion in this position, the seat section is partially supported at each end by an angle bracket 40 projecting inwardly from the frame end. At the front of the seat section in the seat position is another support 85 secured to each frame end having an upper projection 86 which engages the adjacent side bar 21 of the seat section and a lower inner projection 87 which may extend further inwardly to en-

gage the outer edge of the outer section 17 in its folding position as shown more clearly in Fig. 1.

In unfolding the bed from a seat position, the pivoted latches or latch 23 is first disengaged from the holding notch 24 and the latch is moved parallel with the cross bar 22. The front of the seat section is manually raised carrying the seat sections 16 and 17 therewith and assisted by the springs 42. Since the bed sections are all mounted to swing in the frame upon the members 31 and 35 and the sections 16 and 17 are held in right angled position and are suspended by the links 50 and 58 and coordinating levers 54 at each end of the sections, the upward movement of the seat section 15 swings the other two sections upwardly and forwardly free from engagement with the upper edge of the fixed front board 12 in a path substantially as shown by Fig. 2 at which time the coordinating linkage comprising the lever 54 and the short link 58 have guided the overturning movement of the seat section because of the connection of the lever with one end of the side bar 21 and because of the swinging movement of the seat section upon the links 31 and 35 as guided by the short link 58 connected to the plate 37 and as directed by a swinging movement of the coordinating lever 54 attached thereto.

This preliminary movement of the seat, intermediate and outer sections together for the first portion of the swinging movement of the sections does not materially affect the relation of the sections 16 and 17 until after they pass upwardly and outwardly over the top of the front board to the position as shown in Fig. 2. At this time they are movable relatively away from the section 15 and the connecting links 50 and levers 54 are automatically effective first to swing the sections 16 and 17 outwardly and downwardly until the legs 70 engage the supporting surface for the article of furniture at which time the seat section is completing its overturning movement as shown in Fig. 3 and all of the sections are substantially supported by the inner legs 70 as the outer section 17 continues its downward movement as controlled by the coordinating linkage which conducts the seat sections and the other sections.

In the folding movement of the sections to form a seat, the unfolding action is reversed. The operator raises upwardly at the outer side of the outer section 17 which raises the legs 78 and commences to fold them when the outer section is in a partially raised position as shown in Fig. 3 at which time the coordinating linkage has also partially raised the seat section to the position therein shown and the continued upward raising movement of the outer seat section then folds the legs 78, raises and folds the legs 70 and swings the adjacent connected end of the seat section downwardly to a position as shown in Fig. 2. Continued inward movement moves the sections 16 and 17 to a right angled position at the end of the seat section and all of the sections are then swung upon the members 31 and 35 inwardly below the seat section. The intermediate and outer sections are supported in this right angle position by the coordinating linkage parts 50 and 54, the seat section is firmly supported by the brackets 40 and 85 and the link 31 is positioned at the side of the frame bar 21 in the space provided by the spacing plate 25.

As the outer section 17 is moved into alignment, the outer legs 78 are likewise moved downwardly and when the aligning movement is complete, the intermediate and outer sections are firmly supported by their legs and the seat section is firmly supported at each side by the two mounting links 31 and 35 and also by the coordinating linkage which extends firmly between the intermediate section and the seat section since both the link and the lever are firmly pivoted to the seat section and the intermediate section. Thus the operation of the coordinating linkage comprising the links 50, the levers 54 and the short connecting links 58 control the folding movement of all of the sections from the start to the finish in either direc-

tion, the manual engagement thereof being only for the purpose of furnishing the motive power.

While a preferred embodiment of this invention has been described in some detail, it should be regarded by way of illustration and example rather than a restriction or limitation thereof, as many changes in the construction, combination and arrangement of the parts may be made without departing from the spirit and scope of the invention.

10 I claim:

1. In a convertible seat bed comprising a supporting frame, a seat section and means for mounting in the frame to overturn rearwardly therein, an intermediate bed section and an outer bed section pivoted together, a front board fixed in the frame across the front thereof and extending upwardly to the top of the seat section when folded therein and in the normal path of the bed sections in their unfolding and folding movements folding leg structures pivoted to the said intermediate and outer sections, and means connecting the seat section and the intermediate and outer sections having a coordinating connection with the said mounting means for the seat and with the leg folding structures for automatically swinging the intermediate and outer section upwardly and forwardly from a position below the seat over the upper edge of the front board and unfolding them into alignment with the seat section as the seat section is overturned rearwardly.

2. In a convertible seat bed comprising a supporting frame, a seat section, an intermediate section and an outer section, means mounting the seat section in the frame for overturning rearwardly from the front edge thereof, a front board fixed in the frame across the front thereof and extending upwardly to the top of the seat section when folded therein and in the normal path of the bed sections in their unfolding and folding movements, means for pivotally connecting the intermediate section and the outer section for hinging movement from a position at right angles to each other to a position at right angles to each other to a position in alignment with each other, a coordinating linkage connecting the intermediate and outer sections to the seat section and to the mounting means for the seat section for swinging the intermediate section and the outer section from a right angle position below and at the rear of the seat, upwardly and forwardly over the top of the front board as the seat is overturned rearwardly to an aligned position with the seat section overturned rearwardly, and the intermediate and outer sections in alignment in front of the seat section.

3. In a convertible seat bed comprising a supporting frame, an invertible seat structure, a pair of links upon which the seat section is mounted for overturning movement rearwardly in the frame, a front board fixed in the frame across the front thereof and extending upwardly to the top of the seat section when folded therein and in the normal path of the bed sections in their unfolding and folding movements, a pair of bed sections hinged together for movement from a position at right angles to each other to a position in alignment with each other and a coordinating linkage connecting the seat section, its mounting links and the pair of seat sections for swinging the seat sections from a right angle position below and behind the seat section upwardly and outwardly from below the seat section and freely over the top of the front board to a position in alignment therewith when the seat section is overturned.

4. In a convertible seat bed comprising a supporting frame, an invertible seat section, a pair of members upon which the seat section is mounted for rearwardly overturning movement in the frame, a pair of pivotally connected bed sections movable from a position at right angles to each other below and partially behind the seat section in its seat position to a position in alignment in front of the seat, an upwardly extending front board fixed at the front of the frame and means comprising a link and a lever connecting the members for the seat section to

the pair of bed sections for automatically moving them from a folded position below and partially behind the seat swinging them upwardly and outwardly over the top of the front board when the seat is overturned and extending the said pair of sections into alignment with the seat in its overturned position to form a bed.

5. In a convertible seat bed comprising a supporting frame, a seat section and a pair of bed sections, a pair of members to mount the seat for overturning movement, legs pivoted to the other two sections, a front board secured at the front of the frame and extending upwardly therein to the top of the seat section when it is folded therein and in the normal path of the bed sections in their unfolding and folding movements, a coordinating linkage connecting the sections, the folding legs and the folding links for the seat section and comprising a lever joining the seat section to one of the other sections, and a link joining one end of the lever to one of the mounting members for the seat section for automatically coordinating the movement of the bed sections to swing the said pair of sections upwardly and outwardly from a position at right angles to each other below and behind the seat section and over the top of the front board to a position in which the three bed sections are aligned in front of the seat section and supported by the folding leg structures.

6. In a convertible seat bed comprising a supporting frame, an invertible seat section and a pair of members upon which the section is invertibly mounted to swing rearwardly in the frame, a front board fixed at the front of the frame an intermediate bed section and a supporting leg structure therefor, an outer bed section and a folding leg structure for supporting it, means connecting the folding leg structures and a coordinating linkage comprising a lever, and a short link connected to one of the pair of members for mounting the seat section and connected to the intermediate section and to the means for operating the folding leg structures to swing the intermediate and outer sections from a position at right angles to each other with their legs folded and in a position below and partially behind the seat structure upwardly and over the top of the fixed front board to an extended position with the legs unfolded to support the sections and the sections thereof in alignment with the seat section in its overturned position.

7. In a convertible seat bed, a seat frame, a foldable structure comprising a seat section and a pair of members for mounting the seat section to overturn rearwardly in the frame, a front board secured at the front of the frame and extending upwardly therein to the top of the seat section when it is folded therein and in the normal path of the bed sections in their unfolding and folding movements an intermediate bed section and an outer bed section hinged together for movement from a position at right angles to a position in alignment with each other, a folding leg structure for the intermediate section and for the outer section, means connecting the legs and their respective sections for folding and unfolding the legs as the sections are relatively moved, and coordinating linkage comprising a pivoting link connecting the seat section with the intermediate section and a lever also connecting the seat section with the intermediate section, means connected to one end of the lever for engaging one of the pair of members for operating the seat section and the other end of the lever engaging the means for operating the said leg folding means for the intermediate and outer sections to automatically control the movements of all the sections and to swing the intermediate and outer bed sections over and free from contact with the front board when the seat section is overturned in one direction or the other.

8. In a convertible seat bed comprising a supporting frame, a seat section and link means to mount it for rearward inverting movement in the frame, a front board

fixed across at the front of the frame and extending upwardly, an intermediate bed section and an outer bed section hinged together for joint folding movement from a position at right angles to each other within the frame to a position in alignment at the front of the frame, supporting legs pivoted to the intermediate section and the outer section and leg folding structure connected to the legs and the sections for folding and unfolding the legs as the sections are folded at right angles and extended, a link pivotally connected at one end to one end of the intermediate section and at the other end to the seat section, and coordinating means comprising a lever also pivoted to the end of the intermediate section and the end of the seat section, the lever having an extension at one end and a link connecting this extension with the overturning link means for the seat and the lever having an extension at the other end connected to the said leg folding means of the intermediate and outer sections, the coordinating connection being operative to swing the intermediate and outer sections from a position with the legs folded against the respective sections at right angles to each other and in a position below and behind the seat upwardly and freely over the top of the front board to a position with the intermediate and outer sections in alignment and in front of the seat in overturned position with the legs extended to support the intermediate and outer sections.

9. In a convertible seat bed, in accordance with claim

8, the linkage for mounting the seat section for over-

turning, comprising a plate to which the said short link

coordinating link is pivoted, the plate having a stop there-

on to engage the short link intermediate its ends to limit

its movement in one direction.

10. In a convertible seat bed, in accordance with claim

8, the linkage for mounting the seat section including

a plate with an abutment extending outwardly there-

from, a supporting member connected to the seat section

and projecting therefrom upon which one end of the

plate is pivoted and the abutment of the plate engaging

the support to limit the movement of the seat section

to a position in alignment with the other sections when

it is moved relatively thereto by the said coordinating

means.

11. In a convertible seat structure, in accordance with

claim 8, the seat section comprising a pair of end bars

and a yoke connected at its ends to corresponding ends

of the bars for spacing them apart, a brace connected

to each end bar and to the adjacent side of the yoke

at a distance from the end bar to hold the yoke firmly

and the said link connecting the seat section and the

intermediate section being pivoted to the outer portion

of the yoke in fixed relation to the section and at a

spaced distance from the said coordinating lever.

12. In a convertible seat bed, a seat frame having

ends spaced apart at the front and a fixed front board

engaging the front ends of the ends for holding them

in spaced relation, a rearwardly overturning seat section

and linkage connected to the seat ends for overturning

the seat section rearwardly in the frame, a pair of bed

sections pivoted together and movable from a position

at right angles to each other in the frame to a position

in alignment and at the front of the frame, folding

legs connected to each of the pair of sections, means

for folding and unfolding the legs as the pair of sections

are folded and extended, a fixed linkage between the

seat section and one of the pair of sections and a co-

ordinating connection between the seat section and one

of the pair of bed sections, the coordinating connection

comprising a lever also having connection with the leg

operating means and having a link connecting it with

the seat overturning linkage, the overturning movement

of the seat being automatically operated through the

coordinating connection to swing the pair of bed sec-

tions from a position at right angles with each other

below the seat and partially behind it to a position up-

wardly and outwardly over and clear of the upper edge of the fixed front board and to swing outwardly and downwardly unfolding the legs to support the said pair of sections as the sections are moved into alignment.

13. In a convertible seat structure, in accordance with claim 12, the coordinating linkage being operative to maintain the said pair of bed sections substantially at right angles to each other until they pass over the top of the front board in swinging into and out of the frame, and the leg folding construction being operative to engage the leg of the first connected section with the surface upon which the frame is also supported in advance of the engagement of the leg of the other section with said surface.

14. A structure, in accordance with claim 12, in which the said pair of sections in folded position are disposed below and at the rear of the seat section within the frame and the front of the seat section within the frame is below the level of the top of the front board, and the seat section has a cross rail with latches thereon and the front board has notches engageable by the latches to hold the seat construction folded within the frame.

15. A convertible seat structure having a supporting frame with a fixed front board, a multi-section bed frame comprising one section and means to mount it for rearwardly overturning swinging movement in the frame, a plurality of the other sections being pivoted together for relative folding and swinging movement into and out of the frame, and coordinating means connected to the seat section and to the mounting means and to the other sections for automatically coordinating the movements of all of the sections to swing the sections upwardly and clear of the top of the front board in the unfolding movement of the sections.

16. A seat structure, in accordance with claim 15, in which the said plurality of other sections have pivoted leg structures foldable from an extended supporting position at right angles to the sections to positions parallel to the

same sections, and connections from the leg structures with the said coordinating means to automatically fold and unfold the leg structures as the sections are folded and unfolded thereby so they will also clear the top of the front board.

17. A convertible seat bed having a supporting frame with a fixed front board extending upwardly, a multi-section bed frame comprising a seat section and a plurality of other sections interconnected for relative folding and swinging movement into and out of the frame, means to mount the seat section for rearwardly overturning movement in the frame, said mounting means including one link pivoted to the supporting frame at each side and to the upper rear portion of the seat section when in the seat position and extending to elevate the seat section in the frame in its swinging movement, and to guide the other sections to fold into and out of the frame below the seat section and above the fixed front board in the folding and unfolding movement of the sections.

18. A convertible seat bed having a supporting frame, a multi-section bed frame comprising a seat section and means to mount it for rearwardly overturning movement in the frame, a plurality of the other sections being pivoted together for relative folding and swinging movement into and out of the frame, and coordinating means connected to the mounting means of the seat section and to the other sections for automatically coordinating the movements of all of the sections and the mounting means in swinging the said other sections below the seat section into and out of the frame in folding and unfolding the bed.
